UNITED STATES PATENT OFFICE.

ALEXANDER E. REDLICH, OF CHICAGO, ILLINOIS.

BOTTLE-STOPPER.

No. 852,242.

Specification of Letters Patent.

Patented April 30, 1907.

Application filed March 1, 1907. Serial No. 359,969.

To all whom it may concern:

Be it known that I, ALEXANDER E. REDLICH, a citizen of the United States, residing at Chicago, in the county of Cook and State 5 of Illinois, have invented a new and useful Bottle-Stopper, of which the following is a specification.

The principal object of the present invention is to provide a novel and attractive 10 form of bottle and bottle stopper, intended principally for display or advertising purposes, and wherein the stopper serves as a support or carrier for a drinking glass or similar receptacle, and an advertising dial.

15 A further object of the invention is to provide a combined bottle stopper and drinking glass support.

With these and other objects in view, as will more fully hereinafter appear, the invention consists in certain novel features of construction and arrangement of parts, hereinafter fully described, illustrated in the accompanying drawings, and particularly pointed out in the appended claims, it being 25 understood that various changes in the form, proportions, size and minor details of the structure may be made without departing from the spirit or sacrificing any of the advantages of the invention.

30 The accompanying drawing illustrates in sectional elevation a bottle stopper constructed in accordance with the invention.

The bottle 10 may be of any desired size and shape and is closed by a stopper preferably in the form of a cork 11. This stopper is secured by a screw 12 to the lower end of a bracket 13, said bracket being formed of wood or metal and being provided with an obliquely disposed arm 14 from which projects 35 a second screw 15. The screw 15 carries a semi-spherical block 16 from which projects an annular flange 17 and the block is provided with a recessed face into which is screwed the plug-like end of a cylindrical casing 18.

40 The casing 18 is designed for the reception of a drinking vessel which, in the present instance, is shown in the form of a small glass tumbler x , and the tumbler may be readily removed from the receptacle and used to receive 45 a portion of the contents of the bottle.

To add to the ornamental appearance, the bracket 13 is provided with a projecting arm 20 on which is hung an elongated cylindrical block 21 having an enlarged lower end, said block being connected to the bracket by a 50 flexible cord 22.

The bottle may be arranged to contain liquors, cordials, wine, or the like, and by grasping the bracket 13 the cork may be readily withdrawn from the bottle and a portion of its contents poured into the tumbler x , the latter being removed from the receptacle 18, or being allowed to remain in the receptacle, as desired.

It will be noted that the annular flange or disk 17 may serve as a means for displaying advertising matter, so that the stopper may perform the three functions of a closure for the bottle, an advertising means, and a glass support or holder.

It will be understood that the bottle may be employed as a receptacle for perfume, candy, liquors, cordials, wine and the like.

I claim:

1. A bottle stopper, and a drinking vessel 5 support carried thereby.

2. A bottle stopper, a bracket to which the stopper is secured, and a drinking vessel receptacle supported by the bracket.

3. In combination, a bracket, a bottle 80 stopper secured to one end thereof, and a drinking vessel support secured to the opposite end of said bracket.

4. In combination, a bracket having an obliquely disposed arm, a stopper or cork secured to one end of the bracket, and a drinking vessel support secured to the obliquely disposed arm.

5. In combination, a bracket having an obliquely disposed arm, screws projecting 90 from the lower end of the bracket, and the upper end of the arm, a cork or stopper carried by the lower screw, a block secured to the upper screw, and an approximately cylindrical drinking vessel support carried by 95 said block.

6. A bottle stopper carrying an advertising dial, and a drinking vessel support.

7. A bottle stopper having a bracket to which is secured a receptacle for a drinking 100 vessel surrounded by an annular advertising dial.

In testimony that I claim the foregoing as my own, I have hereto affixed my signature in the presence of two witnesses.

ALEXANDER E. REDLICH.
